LIFE RAFT RELEASING MECHANISM

Arthur N. Anderson, Brooklyn, N. Y.

Application January 28, 1944, Serial No. 520,639

12 Claims. (Cl. 9—33)

1

This invention relates to multiple release for rafts or floats. It is particularly directed to a quick releasing device for releasing square or doughnut type floats from the sides of ships.

Considerable difficulty has been encountered in dropping floats or rafts from ships fast enough in an emergency, thereby preventing quick getaway of the raft from a sinking or burning ship. It is, therefore, an object of this invention to provide highly improved means to support and release such floats without any chance of fouling, the construction being such that the rafts can be released even if the ship lists considerably.

Another object of this invention is to provide a float support so arranged that if the ship sinks the rafts will float off their supports without launching or necessity for manually releasing the rafts.

Another object of this invention is to provide means for mounting the floats or rafts against the side of the ship, singly or in pairs of superposed floats, means being provided to release the floats mounted in pairs one at a time, the release construction being such that the floats are released top and bottom so that there is no chance of the supporting rope fouling.

Still a further object of this invention is to provide a float supporting and releasing means of the character described, in which a single operator actuating one control device can release a number of pairs of floats supported along the side of a ship.

Yet another object of this invention is to provide strong, rugged and durable float supporting and releasing means of the character described which shall be relatively inexpensive to manufacture, easy to manipulate, and yet practical and efficient to a high degree in use.

Other objects of this invention will in part be obvious and in part hereinafter pointed out.

The invention accordingly consists in the features of construction, combinations of elements, and arrangement of parts which will be exemplified in the construction hereinafter described, and of which the scope of application will be indicated in the following claims.

In the accompanying drawing, in which is shown one of the various possible illustrative embodiments of this invention,

Fig. 1 is a front elevational view of the side of a ship showing two pairs of floats provided with supporting and releasing devices embodying the invention.

Fig. 2 is a cross-sectional view taken on line 2—2 of Fig. 1.

2

Fig. 3 is a front elevational partial view of the shaft or rod which extends along the side of a ship and onto which the supporting ropes are hooked.

Fig. 4 is a cross-sectional view taken on line 4—4 of Fig. 3.

Fig. 5 is an enlarged cross-sectional view taken on line 5—5 of Fig. 1.

Fig. 6 is a cross-sectional view taken on line 6—6 of Fig. 5.

Fig. 7 is an enlarged view of the control device for releasing the floats.

Fig. 8 is a cross-sectional view taken on line 8—8 of Fig. 7.

Fig. 9 is a cross-sectional view taken on line 9—9 of Fig. 7.

Fig. 10 is a view similar to Fig. 7 but illustrating a modified construction.

Fig. 11 is a cross-sectional view taken on line 11—11 of Fig. 10.

Fig. 12 is a side elevational view of the pelican hook for the supporting rope or cable which may be used in emergencies.

Fig. 13 is a view similar to Fig. 12 but showing the pelican hook opened up.

25 Referring now in detail to the drawing, 10 designates the side of a ship comprising an upper deck 11 and a lower deck 12. In the drawing, 13 designates one side of the ship supporting the lower deck. On the upper deck is the ship rail 14.

30 Means is provided to support the floats or rafts 16 in superimposed or stacked pairs against the side of a ship. To this end there is attached to the outer side of the ship wall 13 pairs of similar, symmetrical pivoted or hinged brackets 18.

35 Each pair of brackets 18 have aligned openings 19. The axes of the pivoted openings 19 of each of brackets are inclined to one another, for the purpose hereinafter appearing. Pivoted to the pair of brackets 18 are a pair of similar hooks 20.

40 Each hook 20 has pintles 21 journaled in the openings 19. The hooks 20 are curved to engage the outer surface of one of the floats 16.

At the outer end of hook 20 are parallel hinge lugs 23 formed with aligned hinged openings 24. 45 Pivoted to the lugs 23 of each hook 20 is a second hook 25 adapted to engage the second float or raft 16. Hook 25 has a pair of pintles engaged within the pivoted opening 24.

At the outer end of each hook 25 is a downwardly curved hooked portion 26 for the purpose hereinafter appearing. It will be noted that the floats 16 are each supported on opposite sides of the lower end thereof by pairs of hooks 20, 25.

Supported on brackets or hangers 30 extending down from the upper deck 11 is an elongated

horizontal shaft or rod 31. Rod 31 extends along the side of the ship and is rotatably mounted in suitable bearings in the hangers 30. On the rod and above each pair of floats 16 are a pair of upstanding lugs 34, 35. The lugs 34 and 35 are spaced from one another; and lug 34 is normally inclined forwardly and upwardly whereas lug 35 extends straight up. The lugs are thus radial relative to the rod 31 and at an angle to each other.

To support the inner float or raft 16 there is provided an endless wire rope or cable 40 hooked over the lug 35 and passing between the two floats, and engaging the upper end of the inner float and around the lugs 23. The wire rope thus pulls up on the hooks 20 which support the underside of the float, and said wire rope also engages the upper end of said float. When drawn taut the wire rope loop is substantially triangular in shape, the base of the triangle being the part between lugs 23.

To support the outer float 16 there is provided a wire rope or cable 41. The wire rope or cable 41 is hooked over the lug 34 and passes over the outer side of said float and is hooked onto the hooked portions 26 of the hooks 25. The wire rope 41 is likewise endless and substantially triangular in shape as shown in Fig. 1 of the drawing. The hooks 25 thus support the lower end of the outer float whereas the rope 41 engages the upper end of said float to keep it against the inner float.

At the lower end of the railing there may be provided backboards 45 attached to the ship and having semi-circular cut-outs to engage the rear floats 16 to hold them against side movement.

Means is provided to first release all of the outer floats 16 simultaneously and then all of the inner floats 16 simultaneously. To this end there is attached to the underside of the upper deck 11, a bracket 50 provided with a vertical guide 51. Slidably mounted in the guide 51 is a rack 52. Attached to the guide 51 are ears 53 having openings 54 in which the rod 31 is journaled.

Fixed to the rod 31 is a gear 56 meshing with rack 52. Attached to the upper side of the deck 11 is a base plate 57 and fixed thereto is a vertical upstanding tube 58. The plate 57 as well as deck 11 is formed with registering through openings, and extending through said openings is a vertical rod 60 contacting the upper end of the rack 52. Said rod 60 extends upwardly above the tube 58 and is provided with an offset handle 61 extending at right angles to said rod.

Fixed to the upper end of the rod 60, substantially at the upper end of tube 58 is a transverse pin 64 projecting from opposite sides of said rod. There is also fixed to rod 60 at a point spaced below the transverse pin 64 another transverse pin 65 likewise extending to opposite sides of the rod. Pin 64 is disposed at right angles to pin 65.

The handle 61 is formed with a recess 61a on the underside thereof. Pivoted to the underside of the handle 61 is a bell crank 67 having an arm 68 disposed within the recess 61a. The bell crank 67 has another downwardly extending arm 69 for the purpose hereinafter appearing.

Interposed between arm 68 and handle 61 is a U-shaped spring 70 which tends to rotate the bell crank 67 in a clockwise direction, looking at Fig. 7.

Screwed to the upper end of tube 58 is a cup-shaped cover or cap 73 formed with a central round opening 74 having diametrically opposed slot extensions 75, thus forming a key slot. The

slots 75 are so proportioned that the wings 64 and 65 can pass therethrough, should said wings become aligned with said slots.

The cup 73 is provided with a U-shaped radial lug 78 adapted to receive the lower end of arm 69 of the bell crank 67. The lug 78 extends in the plane of the slot 75. When arm 69 engages within lug 78 the wings 64 are at right angles to the slot 75. To release the outer floats 16, bell crank 67 is pressed up to disengage arm 69 from lug 78. Rod 60 is then rotated about its axis through an angle of 90° to bring the wings 64 into alignment with the slots 75.

It will be noted that the pull of ropes 40 and 41 on the lugs 34, 35 tends to rotate the gear 56 in a counterclockwise direction looking at Fig. 7, thereby causing an upward pressure of the rack 52 against the underside of rod 60. As soon as the wings 64 are aligned with the slots 75 therefor, the rod 60 will be pressed or pushed upwardly until the wings 65 contact the underside of the cup 73. This movement of the rack 52 is accompanied by rotation of the gear 56 through a sufficient angle to permit the ropes 41 to disengage from the lugs 34. As soon as said ropes disengage the lugs 34, they will drop down thus releasing the hooks 25 which also drop down about the pivoted lugs 23 thereby entirely releasing the outer floats which drop into the water.

30 The operator may then release the inner floats 16 by again turning the rod 60 through an angle of 90° to bring the wings 65 into alignment with the slots 75 thereby permitting the rack 52 to press the rod 60 upwardly and permitting rotation of shaft 31 and its gear 56. Such rotation of rod 31 will bring the lugs 35 down to such an angle that the inner ropes 40 will disengage therefrom permitting hooks 20 to swing down and thereby releasing the inner floats. Thus the operator can first release all of the outer floats, and then all of the inner floats.

If there is insufficient head room above the upper deck 11 for movement of the rod 60 upwardly during the releasing operation, then the entire releasing mechanism may be reversed and the rack engaged with the outer side of the gear 56 instead of with the inner side. In such case the rod 60 will be pressed downwardly to release the ropes, instead of upwardly.

50 In Figs. 10 and 11 there is shown a modified construction in which bevelled gears are substituted for the gear and rack of Fig. 7. As shown in the drawing, there is attached to the upper deck 11 a base plate 57 formed with a through opening which extends also through the upper deck. Attached to the underside of the upper deck 11 is a bracket 80. Attached to bracket 80 are ears 81 in which is journaled the rod 31. On rod 31 is a bevel gear 83. Also supported by the bracket 80 is a bearing 85 on which is journaled a vertical rod 86.

Splined to said rod 86 is a bevel gear 87 meshing with said bevel gear 83. The bearing 85 may contact the upper side of the bevel gear 87.

Attached to the base plate 57 and extending upwardly therefrom is a tube 88 formed at its upper end with a Z-shaped slot 89. Slot 89 has a horizontal lower portion 90, a vertical portion 91 extending from one end of slot portion 90; and a horizontal slot portion 92 extending from the upper end of vertical slot portion 91, but in an opposite direction to slot portion 90.

Fixed to rod 86 is a radial pin 94 passing through the slot 89. At the upper end of rod 86 75 is an offset handle 95 formed with a recess 95a

on its underside. Pivoted to the underside of the handle 95a is a bell crank 97 having an arm 98 received within the recess 95a. Bell crank 97 also has a downwardly extending arm 99 engaged within a retainer lug 100 at the upper end of the tube 88. Interposed between arm 98 and handle 95 is a U-shaped spring 101 which normally urges arm 99 into the retainer lug 100. When arm 98 is pressed upwardly into recess 95a arm 99 disengages from retainer lug 100, permitting rod 86 to be rotated through a predetermined angle determined by the angular extent of slot portion 90. During such rotation of rod 86, bevel gear 87 will rotate bevel gear 83, thereby rotating rod or shaft 31 about its axis through a sufficient angle to release the outer floats, as described heretofore.

The rod 86 may then be pulled upwardly to bring the pin 94 through slot portion 91 into slot portion 92. Handle 95 may then be turned to rotate rod 86 through another angle determined by the angular extent of slot portion 92, thereby again rotating bevel gear 83 to release the inner floats.

The ropes 40 and 41 may be endless. However, in order to permit release of said ropes in case of emergency, each rope may comprise a length of rope connected together by a pelican hook 110 as shown in Fig. 12 and well known in the art. In Fig. 13, the pelican hook 110 is shown opened up to permit the rope to be released.

It will be noted that the rod 31 may be rotated sufficiently to release the floats even if the ship lists to a considerable extent.

If the ropes 40 and 41 are made of $\frac{3}{8}$ " diameter steel cable they will be sufficiently stiff to allow the rafts to float off from a sinking ship without launching, that is without the necessity of releasing the handles as described hereinabove.

If desired, the floats 60 can be mounted singly. In such case the hooks 25 are omitted and only the inner ropes 49 are used and they are hooked over the lugs 35. In such event furthermore, the outer ends of the hooks 29 may be made like the hook portions 26.

It will thus be seen that there is provided a device in which the several objects of this invention are achieved, and which is well adapted to meet the conditions of practical use.

As various possible embodiments might be made of the above invention, and as various changes might be made in the embodiment above set forth, it is to be understood that all matter herein set forth or shown in the accompanying drawing is to be interpreted as illustrative and not in a limiting sense.

Having thus described my invention, what I claim as new and desire to secure by Letters Patent, is:

1. In combination with a life raft, a pair of hooks pivoted to the side of a ship and engaging the lower end of the life raft at opposite sides thereof, a rod rotatably mounted on the ship and provided with a lug, a rope hooked over said lug and engaging the upper end of the life raft and releasably engaging the outer ends of said hooks, and means to rotate said rod whereby to disengage said lug from the rope to permit the rope to drop, thereby permitting said hooks to swing downwardly about their pivoted ends and release the raft to permit it to drop into the water.

2. In combination with a hook pivoted to a ship and engaging the underside of a life raft, a rod journaled on said ship and above said life raft

and provided with a lug, a rope hooked over the lug and engaging the outer end of said pivoted hook, said rope engaging the upper end of said life raft to hold it against the side of the ship, and means to rotate said rod to disengage the lug from the rope, whereby said rope will disengage the hook and permit it to swing down on its pivot to release the life raft.

3. In combination with a hook pivoted to a ship 10 and engaging the underside of a life raft, a rod journaled on said ship and above said life raft and provided with a lug, a rope hooked over the lug and engaging the outer end of said pivoted hook, said rope engaging the upper end of said life raft to hold it against the side of the ship, and means to rotate said rod to disengage the lug from the rope, whereby said rope will disengage the hook and permit it to swing down on its pivot to release the life raft, a second hook pivoted to the outer end of the first hook and engaging the underside of a second life raft superimposed against the side of the first life raft, said rod being provided with a second lug disposed at an angle to the first lug, a second rope hooked over the second lug and engaged with the outer end of the second pivoted hook, said rope engaging the upper end of the second life raft to hold it against the side of the first life raft, said second lug being disposed at such an angle to the first lug so that rotation of said rod will first disengage the second rope from the second lug before the first rope will disengage from the first lug.

4. In combination with a hook pivoted to a ship and engaging the underside of a life raft, a rod journaled on said ship and above said life raft and provided with a lug, a rope hooked over the lug and engaging the outer end of said pivoted hook, said rope engaging the upper end of said life raft to hold it against the side of the ship, and means to rotate said rod to disengage the lug from the rope, whereby said rope will disengage the hook and permit it to swing down on its pivot to release the life raft, a gear on said rod, a rack slidably mounted on said ship and meshing with said gear, a tube fixed to said ship, a member slidably and rotatably mounted in said tube and contacting said rack, means to prevent sliding of said member in said tube, said means being releasable in a predetermined angular position of said member relative to said tube.

5. In combination with a hook pivoted to a ship and engaging the underside of a life raft, a rod journaled on said ship and above said life raft and provided with a lug, a rope hooked over the lug and engaging the outer end of said pivoted hook, said rope engaging the upper end of said life raft to hold it against the side of the ship, and means to rotate said rod to disengage the lug from the rope, whereby said rope will disengage the hook and permit it to swing down on its pivot to release the life raft, a second hook pivoted to the outer end of the first hook and engaging the underside of a second life raft superimposed against the side of the first life raft, said rod being provided with a second lug disposed at an angle to the first lug, a second rope hooked over the second lug and engaged with the outer end of the second pivoted hook, said rope engaging the upper end of the second life raft to hold it against the side of the first life raft, said second lug being disposed at such an angle to the first lug so that rotation of said rod will first disengage the second rope from the second lug before the first rope will disengage from the first lug, releasable means to hold said rod against

rotation, and means to limit rotation of said rod to a predetermined angle upon releasing the same for rotation, whereby to permit disengagement of the second rope with the second lug, said limiting means being releasable to permit further rotation of said rod whereby to permit disengagement of the first rod with the first lug.

6. In combination with a life raft, a pair of hooks pivoted to the side of a ship and engaging the lower end of said life raft at the side thereof, a rod rotatably mounted on the ship above said life raft, a triangularly shaped rope engaging the outer ends of said pivoted hooks and contacting the upper end of the life raft, and means on said rod to engage said rope, whereby to hold the life raft against the side of the ship.

7. In combination with a life raft, a pair of hooks pivoted to the side of a ship and engaging the lower end of said life raft at the side thereof, a rod rotatably mounted on the ship above said life raft, a triangularly shaped rope engaging the outer ends of said pivoted hooks and contacting the upper end of the life raft, means on said rod to engage said rope, whereby to hold the life raft against the side of the ship, and releasable means to prevent rotation of said rod.

8. In combination with a life raft, a pair of hooks pivoted to the side of a ship and engaging the lower end of said life raft at the side thereof, a rod rotatably mounted on the ship above said life raft, a triangularly shaped rope engaging the outer ends of said pivoted hooks and contacting the upper end of the life raft, means on said rod to engage said rope, whereby to hold the life raft against the side of the ship, releasable means to prevent rotation of said rod, and means to permit limited rotation of said rod.

9. In combination with a life raft, a pair of hooks pivoted to the side of a ship and engaging the lower end of said life raft at the side thereof, a rod rotatably mounted on the ship above said life raft, a triangularly shaped rope engaging the outer ends of said pivoted hooks and contacting the upper end of the life raft, means on said rod to engage said rope, whereby to hold the life raft against the side of the ship, releasable means to prevent rotation of said rod, means to permit limited rotation of said rod, said last means comprising a gear on said rod, and a rack meshing with said gear, a tube on said ship, a rod in said tube contacting said rack, said last rod having an offset handle extending outside of the tube, a transverse pin on said second rod and within said tube, and a cover at the upper end of said tube formed with slots adapted to permit said transverse pin to pass therethrough upon rotating said second rod to align said transverse pin with said slots.

10. In combination with a hook pivoted to a ship and engaging the underside of a life raft, a rod journaled on said ship and above said life raft and provided with a lug, a rope hooked over the lug and engaging the outer end of said pivoted hook, said rope engaging the upper end of said life raft to hold it against the side of the ship, and means to rotate said rod to disengage the lug from the rope, whereby said rope will disengage the hook and permit it to swing down on its pivot to release the life raft, a second hook pivoted to the outer end of the first hook and engaging the underside of a second life raft superimposed against the side of the first life raft, said rod being provided with a second lug disposed at an angle to the first lug, a second rope hooked over the second lug and engaged with

the outer end of the second pivoted hook, said rope engaging the upper end of the second life raft to hold it against the side of the first life raft, said second lug being disposed at such an angle to the first lug so that rotation of said rod will first disengage the second rope from the second lug before the first rope will disengage from the first lug, a gear fixed to said rod, a rack meshing with the gear, a tube fixed to said ship, a second rod rotatably and slidably mounted in said tube and contacting said rack, a cap on said tube formed with a keyslot, a pair of longitudinally and angularly spaced pins adapted to pass through said keyslot upon alignment therewith, and a handle on said second rod.

11. In combination with a hook pivoted to a ship and engaging the underside of a life raft, a rod journaled on said ship and above said life raft and provided with a lug, a rope hooked over the lug and engaging the outer end of said pivoted hook, said rope engaging the upper end of said life raft to hold it against the side of the ship, and means to rotate said rod to disengage the lug from the rope, whereby said rope will disengage the hook and permit it to swing down on its pivot to release the life raft, a second hook pivoted to the outer end of the first hook and engaging the underside of a second life raft superimposed against the side of the first life raft, said rod being provided with a second lug disposed at an angle to the first lug, a second rope hooked over the second lug and engaged with the outer end of the second pivoted hook, said rope engaging the upper end of the second life raft to hold it against the side of the first life raft, said second lug being disposed at such an angle to the first lug so that rotation of said rod will first disengage the second rope from the second lug before the first rope will disengage from the first lug, a gear fixed to said rod, a rack meshing with the gear, a tube fixed to said ship, a second rod rotatably and slidably mounted in said tube and contacting said rack, a cap on said tube formed with a keyslot, a pair of longitudinally and angularly spaced pins adapted to pass through said keyslot upon alignment therewith, and a handle on said second rod, and releasable means to retain said second rod against rotation.

12. In combination with a pair of hooks pivotally secured to the side of a ship and engaging the underside of a life raft substantially vertically positioned against the side of the ship, a lug secured to the ship above the life raft, a relatively stiff steel cable hooked over the lug and engaging the outer ends of said pair of hooks, said cable engaging the upper end of said life raft to hold it against the side of the ship, whereby if the ship sinks, the life raft, as it reaches the water, will raise the cable off the lug to release the raft.

ARTHUR N. ANDERSON.
